2,101,336

CIGAR-LIGHTER

Arthur A. Johnson, Bridgeport, Conn., assignor
to Casco Products Corporation, Bridgeport,
Conn., a corporation of Connecticut

Application January 9, 1929, Serial No. 331,163
Renewed May 5, 1937

5 Claims. (Cl. 219—32)

This invention relates to cigar-lighters, and more particularly to the type of cigar-lighter in which the igniting unit is supported on a holder to be brought to incandescence while so supported and to be completely removable for use.

Heretofore, it has been proposed that the heating element of the igniting unit be so mounted therein as to be invisible and inaccessible while supported on the holding device.

10 An object of this invention is to provide a cigar-lighter which has the advantages of the concealed device above referred to but which has the added advantage that while the heating element is normally invisible, it may be viewed when brought to incandescence while supported on the holding device, whereby the user may ascertain whether or not the heating element is being brought to incandescence, and if so, to what degree of incandescence it has been brought.

20 This object is attained by the present invention in the form herein illustrated as exemplary thereof, by providing the supporting means for the heating coil so that the coil may be viewed from either the obverse or reverse sides of the supporting means and by providing a window in the body of the igniting unit which normally does not permit enough light from the exterior of the device to enter the body wherein the heating coil is located to make the latter visible, but 25 which does pass sufficient light from the interior when the heating coil is incandescent to permit the incandescing coil to be seen.

Thus with the device of the present invention, the operator need not remove the igniting unit 30 from the holding device to determine whether or not it is sufficiently hot for his purpose, but may observe this through the window and remove the igniting unit when it is ready for use.

Other features and advantages will hereinafter 40 appear.

In the accompanying drawing, which shows one form of the present invention, that at present preferred—

Figure 1 is a sectional view of the supporting 45 structure, the holding device and the igniting unit of a cigar-lighter made in accordance with the present invention.

Fig. 2 is a plan view of the obverse side of the heating coil and its supporting member.

50 Fig. 3 is a sectional view taken on the line 3—3 of Fig. 1.

Fig. 4 is a front view of the igniting unit, showing the way it appears when the heating element has been brought to incandescence.

55 The device of the present invention illustrated

is particularly adapted for use on a motor vehicle and comprises a holding device and a removable igniting unit. The former, in the form shown herein, comprises a post 14 which has a flange 15 and a screw-threaded rod 17 which, after being passed through a hole provided in the instrument board 16 to receive it, is adapted to receive a washer 18 and a nut 19 by the tightening of which the flange 15 is drawn firmly against the instrument board 16 to securely fasten the holding device thereto. The holding device also comprises a cap 20 adapted to telescopically slide upon a flange 21 on the post 14 and is held thereon against removal by the end of the cap being spun or peened over to engage the edge of the flange 21. Interposed between the end of the cap 20 and the forward end of the flange 21, is a coil spring 22 which holds the cap 20 normally in the position shown in Fig. 1, with the peened over end of the cap in engagement with the flange 21. 20

The holding device has two contacts adapted to be engaged by cooperating contacts on the removable igniting unit. One of these contacts is constituted by the cap 20, while the other is a contact 23 centrally located on the end of the cap 20 and insulated therefrom. Normally, the contact 23 is dead, i. e. does not carry current, for it is out of engagement with a live contact 24 carried by an insulating sleeve 25 forced into a hole in the end of the post 14 and electrically connected to a feed wire 26 leading to a source of E. M. F.

When the igniting unit is supported on the cap 20 and the latter, through the medium of the igniting unit, is slid by hand toward the instrument board, a contact 27 connected with the contact 23 is moved into engagement with the live contact 24, thus causing current to flow to the removable igniting unit. Upon release of the pressure on the cap 20, the spring 22 returns the cap to normal position, opening the circuit leading to the igniting unit by causing a gap to occur between the live contact 24 and the contact 27 of the normally dead contact 23 on the holding device. 40

The igniting unit shown includes a heating element, in the form of a spiral coil of high resistance wire 28 supported on a disk 29 of mica, or other suitable material, which in turn is carried by a perforated metal disk 30. The outer end 50 of the heating element coil is secured to the metal disk 30 at 31 while the inner end is pinched in a transverse slot in the end of the metal pin 32 which extends through the mica disk 29 and the metal disk 30 and receives a nut after the in- 55

sertion of insulated material 33 between the pin and the plate 30.

This heating element 28 is mounted in a body member 34 which comprises two parts 34a and 34b, said parts being provided with cooperating screw-threads 35 by means of which they are held together. The part 34a of the body has a central bore 36 extending through it from end to end, while in the part 34b there is provided a chamber 37 and an end wall 38. This central bore 36 and chamber 37 forms a cavity which is open at one end 39 of the body and closed at the other end by the wall 38. The heating coil 28 is located within this cavity and is held in place adjacent the inner end of the bore 36 in the part 34a by the clamping action resulting from the tightening of the screw-threads 35 when the parts 34a and 34b are assembled in a manner more fully explained below. The central bore 36 in the part 34a is so shaped as to permit the insertion of the end of a cigar or cigarette which may thus be brought into direct contact with the coil of wire 28 of the heating element, for the latter is placed in the cavity so as to face the end 39 of the body. The part 34b also constitutes a shield to prevent draughts of air from quickly cooling off the heating element and also acts as an ash guard to catch any ashes that may fall off a cigar or cigarette in the act of reigniting the same.

In order to conceal the heating element from view, it is mounted on the holding device so that the end 39 of the body lies adjacent to the instrument board 16 while the end wall 38 of the body faces persons sitting in the car.

The mounting of the removable igniting unit to obtain these results is, according to the invention disclosed in an application of Joseph H. Cohen, Serial No. 304,746, filed September 8th, 40 1928, now Patent No. 1,710,348, dated April 23, 1929 accomplished by shaping the bore 36 in the body so that the post 14 and cap 20 may enter the same and engage bearing surfaces provided on the wall of the cavity. These bearing surfaces may be constituted by the internal wall of the part 34a itself, if desired. Preferably, and in order that the removable igniting unit may be frictionally held on the cap 20 of the holding device against accidental removal, the cavity 36 50 is made slightly oversize and there is interposed between the cap 20 and the internal wall of the part 34a a slit sleeve 40 of springy material and so biased as to tend to move away from the internal wall of the part 34a. This sleeve 40 is provided with a flange 41 adapted to engage the disk 30 of the heating element.

The heating element, in addition to the disk 30, is provided with a spider 42 having a central portion inserted between the insulation 33 and the disk 30 and making electrical contact with the latter. The arms of the spider are of such length that when the heating element is placed in the chamber or cavity 36, the arms engage a circumferential shoulder 43 on the part 34b. Hence, when the part 34a is screwed in place, the pressure of the flange 41 of the slit sleeve 40 causes the spider arms to yield and take up any looseness which may exist as the result of minor inaccuracies in the manufacture of the parts.

With the parts assembled as shown, when the removable igniting unit is placed on the cap 20 of the holding device, opposite sides of the sleeve 40 yield and engage the surface of the cap 20 with sufficient pressure to hold the igniting unit thereon against accidental removal.

The removable igniting unit has two contacts adapted to continuously engage two contacts on the holding device when the igniting unit is slid home on the cap as far as it will go without moving the cap. One of these contacts is constituted by the slit sleeve 40 which engages the cap 20 on the post 14 and the other is the pin 32 which holds the center of the heating coil and which engages the contact 23 on the cap 20. Thus it will be seen that in addition to serving as the bearing surface for the removable igniting unit, the slit sleeve 40 also constitutes one of the contacts of the removable igniting unit.

In order to provide for guiding the end of the cigar or cigarette to the heating element, the end 39 of the part 34a has a bevelled surface and the end of the sleeve 40 is belled out slightly so as to be coextensive with said bevelled surface. To prevent a cigar or cigarette from catching on the end of the sleeve, the body part 34a is provided with a shoulder or under-cut behind which lies the end of the sleeve.

In using the device, the operator may grasp it by hand obtaining purchase in the circumferential groove of the body 34, or he may push directly on the wall 38 with his fingers. If the former method is employed, however, the position of the igniting unit need not be changed in the user's hand, for it may be slid off the cap 20 and then the hand may be turned to bring it 30 against a cigar or cigarette held in the mouth ready to be ignited.

In the device shown in the prior application above referred to, the user must either guess at when the heating coil has been brought to the 35 desired degree of incandescence or he must remove the igniting unit from the holder to ascertain it.

According to the present invention, however, he must needs do neither, yet the heating coil is 40 inaccessible and concealed from view while supported on the holder and is not incandescent.

To accomplish this, the present invention provides in the end wall 38 of the body 34, a window 44 which is preferably, although not essentially, 45 made of glass. This window is of such size or of such thickness or of such color that insufficient light passes through it from the exterior of the body to illuminate the interior and permit it to be seen.

To further accomplish the object of this invention, the heating element is so arranged and formed that the heating coil 28 may be viewed from either the observe side (shown in Fig. 2) or the reverse side (shown in Fig. 3) of the heating element. To do this, the insulating disk 29 is 55 preferably made of transparent mica, and the disk 30 is provided with one or more sight-openings 45; and, likewise, the arms of the spider 42 60 are cut-away at 46, or initially so formed, as to avoid materially obstructing the passage of light emanating from the heating coil through the sight-opening 45.

As stated above, normally the interior of the body is invisible, for sufficient light does not enter the body through the window 44. When, however, the heating coil 28 is brought to incandescence, sufficient light is produced thereby to permit the outlines of the convolutions of the coil to be seen through the window 44, as indicated in Fig. 4. In this way, the progress of the coil in becoming incandescent may be watched. Moreover, the degree of incandescence to which the heating coil has been brought may be determined 70 75

by observing the appearance of the coil through the window.

Of course, if desired, the front portion of the wall 38 in the part 34b may be itself made of transparent material such as a phenol-condensation product. However, when a separate glass is employed, as is shown, it is preferable that it be provided with a bezel 47 which holds it in place.

The window may be plain, or it may be in the form of a lens capable of magnifying the appearance of the incandescent heating coil, so that it may be seen for a greater distance and from a more oblique angle.

Variations and modifications may be made within the scope of this invention and portions of the improvements may be used without others.

Having thus described the invention, what is claimed as new and for which it is desired to obtain Letters-Patent, is:—

- 20 1. A cigar-lighter heating element comprising a coil of high resistance wire adapted to be brought to incandescence when connected to a suitable source of current, and a metal disk on which said coil is supported, and a spider attached to said disk, said spider and disk having a sight-opening therein so that the degree of incandescence of the coil may be ascertained whether the disk is viewed from the obverse side on which the coil is supported or from the reverse side.
- 30 2. A cigar lighter comprising a coil of high resistance wire adapted to be brought to incandescence when connected to a suitable source of current; a metal disk on which said coil is supported; and a spider-like member attached to said disk, said spider-like member and disk having the sight opening therein so that the degree of incandes-
- 35

cence of the coil may be ascertained whether the disk is viewed from the obverse side on which the coil is supported or from the reverse side.

3. A cigar lighter comprising a coil of high resistance wire adapted to be brought to incandescence when connected to a suitable source of current; a disk on which said coil is supported and a spider attached to said disk, said spider and disk having sight openings therein so that the degree of incandescence of the coil may be ascertained whether the disk is viewed from the obverse side on which the coil is supported or from the reverse side. 10

4. A cigar lighter comprising a coil of high resistance wire adapted to be brought to incandescence when connected to a suitable source of current; a spider-like member attached to said coil to support the same, said spider-like member having a sight opening therein so that the degree of incandescence of the coil may be ascertained whether the disk is viewed from the obverse side on which the coil is supported or from the reverse side. 15

5. A cigar lighter comprising a coil of high resistance wire adapted to be brought to incandescence when connected to a suitable source of current; a spider-like member attached to said coil to support the same, said spider-like member having a sight opening therein so that the degree of incandescence of the coil may be ascertained whether the disk is viewed from the obverse side on which the coil is supported or from the reverse side; and a lens mounted thereon to receive the light passing through the sight openings. 20 25 30 35
